(57) **CLAIM**

The ornamental design for an in-ear device as shown and described.

DESCRIPTION

FIG. 1 is a front, top, and right side perspective view of an in-ear device showing my new design;
FIG. 2 is a front elevation view thereof;
FIG. 3 is a rear elevation view thereof;
FIG. 4 is a right side elevation view thereof;
FIG. 5 is a left side elevation view thereof;
FIG. 6 is a top plan view thereof; and,
FIG. 7 is a bottom plan view thereof.

The broken lines shown in FIGS. 1-7 illustrate portions of the in-ear device that form no part of the claimed design.
